BUFFING WHEEL AND METHOD OF
MAKING ITHarry E. Hargy, Sr., Sycamore Township,
Hamilton County, Ohio

Application April 10, 1939, Serial No. 267,064

9 Claims. (Cl. 51—193)

The present invention relates to buffing wheels which are particularly adapted to finish the surface of metals or the like.

It is an object of the invention to provide a method and means of producing a buffing wheel inherently capable of presenting a series of rigid undulations around its peripheral surface when subjected to high rotational speeds and under severe working strains.

Another object of my invention is to provide a wheel having a cross-buffing action, that is, an action produced by the material at the periphery of the wheel striking the work at an angle to the plane of rotation of said wheel coincident with a reciprocating back and forth motion upon the surface of the work transversely of the plane of wheel rotation.

A further object of the invention is to provide an economical and efficient means for producing a buffing wheel having its entire working surface formed in sinuous curves.

A still further object of the invention is to provide a means for reenforcing the buffing wheel comprising my invention.

Other objects will be apparent from the following specification and drawing, in which:

Fig. 1 is a side elevational view of my buffing wheel.

Fig. 2 is a perspective view of the buffing wheel in an intermediate stage of manufacture.

Fig. 3 is a plan view of a disc comprising the wheel.

Fig. 4 is a plan view of a distorted disc which is provided with a V-shaped sector.

Fig. 5 is a plan view of a distorted disc having a V-shaped opening therein.

Fig. 6 is a central cross-sectional view showing a means for mounting three sections of my buffing wheel.

Fig. 7 is a perspective view of a reenforcing plate which may be used with my buffing wheel.

The embodiment of my buffing wheel may be used either singly or as a unit containing more than one wheel.

When I employ a number of buffing wheels as a unit, I shall hereafter refer to each wheel as a section, but for general purposes the terms can be used interchangeably.

My buffing wheel 10 comprises a plurality of superimposed discs 11 made from fabric, paper,

fibrous material, or other substance suitable for buffing purposes. The disc is provided with a slit 12 (Fig. 3) which extends inwardly from the periphery of the disc and is preferably disposed along a radial line of the disc. As indicated

in Fig. 5, the opposed edges 13 and 14 of the disc

are then spread circumferentially apart to distort said disc from its normal plane, such as by an undulation 15.

A number of distorted discs formed as hereinbefore set forth are superimposed one upon the other, as indicated in Fig. 2, so that the V-shaped openings 17 formed therein are disposed about the wheel in other than transverse alignment. When the desired thickness of buffing wheel has been formed by superimposing the 10 discs, the stack so formed is provided with a means for securing the discs of the stack together such as an eccentric row of stitches 18. It will therefore be understood that the linear peripheral edge of the buffing wheel has been 15 increased so that the circumference of the composite wheel is greater than the circumference of its individual discs. This increase of circumference in the finished wheel results in the formation of a series of undulations being formed in 20 the peripheral working surface of the wheel which extend inwardly therefrom to its center. When the wheel is rotated at high speed, the material therein tends to seek a flat position at right angles to the rotation thereof, but because 25 of the increased circumference of the wheel, a series of sinuous curves is produced upon its peripheral working surface.

As shown in Fig. 4 the V-shaped portion 17, formed in the disc by distorting it, may be closed 30 by means of a sector 19 which overlaps the edges of the opening and may be sewn or adhesively fastened to the disc along said edges. I contemplate that a distorted disc so formed may be employed as a cover for both sides of a stack 35 of discs having V-shaped openings therein and a row of stitching used to secure the discs and covers together. Further, the disc shown in Fig. 4 may also be used to make a complete buffing wheel.

A buffing wheel so formed may be used either singly or a number of them may be fastened together as a unit as shown in Figs. 1 and 6. As shown in Fig. 6, three buffing wheel sections are coaxially mounted for rotation on a driven shaft 20 and are separated from each other by means of spacers 21. The spacers may be of any thickness less than the transverse distance between the outer edges of opposite undulations formed in the wheels provided, as shown in Fig. 6, the similarly disposed undulations of the sections are positioned in transverse alignment. By spacing the sections apart by a distance not greater than the transverse distance between the outer edges of opposite undulations, full surface 50 55

coverage of the work is provided by a unit of 5
buffing wheels so that said wheels need not be
moved transversely of the plane of rotation of
said wheels. This function is particularly use-
ful on high speed automatic machinery. Because
of the sinuous formation of the wheel and the
fact that it may be spaced a substantial dis-
tance from adjacent wheels, considerable air is
brought to the working surface of the wheel to
10 prevent said wheel from burning or becoming
scorched during operation. Another advantage
of my buffing wheel is due to its increased pe-
ripheral working surface, as it is capable of buff-
ing a surface twice the size of the surface buffed
15 by former wheels of the same thickness. Fur-
ther, its increased striking force on the work
and its cross-cutting action is of great merit in
buffing certain types of metal surfaces.

When wheels of large diameter are used, I
20 prefer to employ rigid spacers 22 (Figs. 6 and 7)
which have undulations 23 formed therein which
conform to the undulations in the vertical sides
25 of my wheel. The plates are secured to both sides
of the wheel by means of the conventional thread-
ed shaft 24 and nut 25 positioned on the driven
shaft 20. In positioning the plates on the shaft,
the undulations in the plate are disposed so as
30 to engage similar undulations in the wheel. As
shown in Fig. 6, the rigid spacers are positioned
35 on either side of a three-sectioned buffing wheel.
It is contemplated that the spacer may be posi-
tioned between a number of buffing wheel sec-
tions, on either side of a single buffing wheel, or
40 in any other manner which will tend to space and
reinforce the buffing wheel to which it is fas-
tened.

What is claimed is:

1. A buffing wheel comprising a plurality of
40 superimposed discs, each disc having a radial slit
formed therein and the opposed edges of the
slit spread apart to form a V-shaped opening
therein, the openings in adjacent discs being dis-
45 posed about the wheel in other than transverse
alignment, a circular cover positioned on both
sides of the superimposed discs and provided with
a radial slit, a sector, the opposed edges of the
slit spread apart and fastened to the edges of
50 the sector, and a row of stitching for securing
the discs and covers together whereby the periph-
eral edge of each disc and cover is distorted from
its normal plane into a series of peripheral edge
undulations disposed on opposite sides of the nor-
55 mal plane of each disc and cover.

2. A buffing wheel comprising a plurality of
55 superimposed discs, each disc having a radial slit
formed therein and the opposed edges of the slit
spread circumferentially apart to form a V-shaped
opening therein, the openings in adjacent discs
being disposed about the wheel in other than
60 transverse alignment, and means for securing the
discs together.

3. A buffing wheel comprising a plurality of
superimposed discs, each disc having a slit ex-
tending inwardly from the periphery thereof, and
having the opposed edges of the slit spread cir-
cumferentially apart to distort the disc from its
normal plane, and means for securing the distort-
ed discs together. 5

4. A buffing wheel comprising a plurality of
superimposed discs, each disc having a slit there-
in and distorted from its normal plane to increase
10 its linear, peripheral edge, means for securing
the discs together to thereby present a series of
peripheral undulations disposed on opposite sides
of the central transverse plane of the wheel.

5. A buffing wheel comprising a plurality of
superimposed discs, means for distorting each
disc from its normal plane to increase the linear,
15 peripheral edge thereof, and means for securing
the discs together to thereby increase the cir-
cumference of the peripheral working surface
20 of the wheel.

6. A buffing wheel comprising a plurality of
superimposed discs, each disc having a slit ex-
tending inwardly from the periphery thereof, and
having the opposed edges of the slit spread apart
25 to distort the disc from its normal plane, a sector
fastened to the edges of the slit, and means for
securing the distorted discs together.

7. A buffing wheel having a number of coaxially
30 disposed sections and each section comprising a
plurality of superimposed discs, each disc having
a slit therein and distorted from its normal plane
to thereby increase its linear, peripheral edge,
means for securing the discs together to thereby
35 present a series of peripheral undulations disposed
on opposite sides of the central transverse plane
of the section, and means for spacing the sections
apart by a distance not greater than the trans-
verse distance between outer edges of opposite
40 undulations, the similarly disposed undulations of
the sections being positioned in transverse align-
ment.

8. A buffing wheel comprising a plurality of
superimposed discs, means for distorting each disc
45 from its normal plane to increase the linear, pe-
ripheral edge thereof, means for securing the
discs together to thereby present a sinuous pe-
ripheral working surface for the wheel, end plates
50 for the wheel having undulations therein which
conform to the undulations in the vertical sides
of the wheel, and means for rigidly securing the
plates to the wheel so that undulations in the
plate engage similar undulations in the wheel.

9. The method of making a buffing wheel which
comprises forming a number of discs from fibrous
55 material, placing a radial slit in each disc, cir-
cumferentially spreading apart the edges of the
slit to distort each disc from its normal plane, su-
perimposing a number of said distorted discs to
form a stack, and stitching the stack together. 60
